UNITED STATES PATENT OFFICE.

GUSTAVE M. FAUSER, OF NEW YORK, N. Y., ASSIGNOR TO THE HOBBS WALL PAPER COMPANY, A CORPORATION OF NEW JERSEY.

DESIGN FOR WALL-PAPER.

50,188.

Specification for Design.

Patented Jan. 16, 1917.

Application filed July 27, 1916. Serial No. 111,724. Term of patent 3½ years.

To all whom it may concern:

Be it known that I, GUSTAVE M. FAUSER, a citizen of the United States, residing in the city of New York, county of New York, and State of New York, have invented a new, original, and ornamental Design for Wall-Paper; and I hereby declare the following to be a description of the same in such terms as will enable persons skilled in the art to which it appertains to make and use the same, reference being had to the accompanying drawings.

In the drawings: Figure 1 is a plan view of a piece of wall paper illustrating my new design. Fig. 2 is an end view.

The design is made up of irregular spaces giving a mottled appearance indicated by

lines of different thickness upon a pebbled surface *b*, *b*. This description is included because otherwise the real scope of the design would not be disclosed.

The irregular pebbled surface, over which the color confining lines pass is shown in Fig. 2 at *b*, *b*.

The design as shown is intended to be repeated or matched out upon all sides indefinitely as is usual in such cases.

What I claim is:—

The ornamental design for wall paper as shown and described.

GUSTAVE M. FAUSER.
